CLAIM

The ornamental design for a printed component curing system, as shown and described.

DESCRIPTION

FIG. 1 is top-front perspective view of a printed component curing system with a top cover of the system in a closed state, showing my design;

FIG. 2 is a top-rear perspective view thereof;

FIG. 3 is a bottom-front perspective view thereof;

FIG. 4 is a front view thereof;

FIG. 5 is a rear view thereof;

FIG. 6 is a right side view thereof;

FIG. 7 is a left side view thereof;

FIG. 8 is a top view thereof;

FIG. 9 is a bottom view thereof;

FIG. 10 is top-front perspective view of a printed component curing system with the top cover of the system in an opened state;

FIG. 11 is a top-rear perspective view thereof;

FIG. 12 is a bottom-front perspective view thereof;

FIG. 13 is a front view thereof;

FIG. 14 is a rear view thereof;

FIG. 15 is a right side view thereof;

FIG. 16 is a left side view thereof;

FIG. 17 is a top view thereof; and,

FIG. 18 is a bottom view thereof.

The broken lines in the drawings depict portions of the design that form no part of the claim.
